[57] CLAIM

The ornamental design for a card holder, as shown and described.

DESCRIPTION

FIG. 1 is a front perspective view of a card holder showing my new design;

FIG. 2 is a top plan view of the holder of FIG. 1;

FIG. 3 is a bottom plan view of the holder of FIG. 1;

FIG. 4 is a front elevational view of the holder of FIG. 1; and,

FIG. 5 is a right side view of the holder of FIG. 1. The rear elevational view is a mirror image of the front elevational view shown in FIG. 4.

The broken line showing of the card and hand are for illustrative purposes only and form no part of the claimed design.

FIG. 1

FIG. 3

FIG. 4

FIG. 5
